UNITED STATES PATENT OFFICE

ABRAHAM GINSBERG, OF NEW YORK, N. Y.

DESIGN FOR A DINING TABLE OR THE LIKE

Application filed April 14, 1933. Serial No. 47,779. Term of patent 7 years.

To all whom it may concern:

Be it known that I, ABRAHAM GINSBERG, a citizen of the United States, residing in the city, county, and State of New York, have invented a new, original, and ornamental Design for a Dining Table or the like, of which the following is a specification, reference being had to the accompanying drawing, forming part thereof.

smaller scale than Figure 1, and the surface decoration shown as covering only a portion of the surface. It is to be understood, however, that this decoration is intended to be symmetrical and that the portions not shown are intended to be similar to but positioned reversely to the corresponding portions that are shown.

I claim:

The ornamental design for a dining table or the like as shown and described.

ABRAHAM GINSBERG.
